[57] CLAIM

The ornamental design for a spoke wheel, as shown and described.

DESCRIPTION

FIG. 1 is a perspective view of a spoke wheel, showing one embodiment of my new design;

FIG. 2 is an end elevation view thereof;

FIG. 3 is a right side elevation view thereof;

FIG. 4 is a left side elevation view thereof;

FIG. 5 is a perspective view of a spoke wheel, showing a second embodiment of my new design;

FIG. 6 is an end elevation view of FIG. 5;

FIG. 7 is a right side elevation view of FIG. 5; and

FIG. 8 is a left side elevation view of FIG. 5.

FIG. 1.

FIG. 2.

FIG. 3.

FIG. 4.

FIG. 5.

FIG. 6.

FIG. 7.

FIG. 8.
